Design No. 11,714, dated March 30, 1880.

UNITED STATES PATENT OFFICE.

FRANK H. SHEPHERD, OF BOSTON, ASSIGNOR TO JAMES W. TUFTS, OF MEDFORD, MASSACHUSETTS.

DESIGN FOR DRAFT-STAND FOR AERATED AND OTHER BEVERAGES.

SPECIFICATION forming part of Design No. 11,714, dated March 30, 1880.

Application filed February 13, 1880. Term of patent 7 years.

To all whom it may concern:

Be it known that I, FRANK H. SHEPHERD, of Boston, in the county of Suffolk and State of Massachusetts, have invented and produced 5 a new and original Design for a Draft-Stand for Aerated and other Beverages, of which the following is a full, clear, and exact description, reference being had to the accompanying photograph, making part of this specification.

In the photograph, A A represent two ornamental pillars or standards, between which is secured an annular casing, B, which contains the draft-cocks d, arranged around it as shown, 15 the casing B and its cocks being supported by the standards A at a suitable height above their bases e, a beautiful and unique design being thus produced.

What I claim as my invention, and desire to secure by Letters Patent, is—

The design for a draft-stand, consisting of the annular casing B, for containing the draft-cocks d, arranged between and supported by the ornamental pillars or standards A A, substantially as herein shown and described. 20 25

Witness my hand this 9th day of February, A. D. 1880.

FRANK H. SHEPHERD.

In presence of—

P. E. TESCHIEMACHER,
W. J. CAMBRIDGE.
